UNITED STATES PATENT OFFICE.

ETHAN I. DODDS, OF CENTRAL VALLEY, NEW YORK, ASSIGNOR TO KERNER MANUFACTURING COMPANY, OF PITTSBURGH, PENNSYLVANIA, A CORPORATION OF PENNSYLVANIA.

PORTABLE PNEUMATIC TOOL.

1,090,603.

Specification of Letters Patent. Patented Mar. 17, 1914.

Application filed January 22, 1913. Serial No. 743,538.

To all whom it may concern:

Be it known that I, ETHAN I. DODDS, a citizen of the United States, residing at Central Valley, in the county of Orange and State of New York, have invented a new and useful Improvement in Portable Pneumatic Tools, of which the following is a full, clear, and exact description, reference being had to the accompanying drawings, forming part of this specification, in which—

Figure 1 is an end elevation partly broken away of a tool embodying my invention; Fig. 2 is a longitudinal vertical section of the same; Fig. 3 is a transverse vertical section on the line III—III of Fig. 2; Fig. 4 is a section on the line IV—IV of Fig. 2; Fig. 5 is a side elevation; and Fig. 6 is an end elevation looking at the opposite end from Fig. 1.

20 My invention has relation to portable pneumatic tools, and is designed to provide a simple, convenient and compact form of tool which may be used for a variety of purposes.

25 The nature of my invention will be best understood by reference to the accompanying drawings, in which I have shown the preferred embodiment thereof and which will now be described, it being premised, however, that various changes may be made in the details of construction and arrangement of the several parts, without departing from the spirit and scope of my invention, as defined in the appended claims.

35 In these drawings, the numeral 2 designates the handle portion of the tool, which is shaped at 2^a to form the grasp for the hand. This portion 2 is made hollow to form the conduit 3, by means of which the motive fluid

40 is led into the motor chamber 4 of the tool. The lower end of the conduit 3 where it opens through the base of the handle portion is shown as interiorly threaded at 5, for the attachment thereto of a supply pipe or hose.

45 The upper member of the handle portion 2 has the depending barrel part 6, formed with a vertical conduit or port 7, which communicates at its upper end with the conduit 3 and at its lower end with the motor chamber 4.

50 A valve seat 8 is formed at the junction of the ports or conduits 3 and 7 to seat a rotary valve 9. This valve has a projecting stem 10 at one end to which is attached

a lever 11, one arm of which extends in position to be readily pressed by the thumb or 55 finger when the tool is grasped by the hand, and to the other arm of which is attached a spring 11^a, which acts to normally hold the valve in the closed position shown in Fig. 2.

The motor chamber 4 is formed in a cylindrical portion 12 of the frame at the lower end of the barrel part 6, and is designed to contain any suitable form of rotary piston. In the device illustrated in the drawings I have shown the motor chamber as provided 65 with two parallel piston shafts 13, each of which carries two rotary pistons 14, of the intermeshing or intergearing type. The port or conduit 7 opens into the motor chamber 4, intermediate the two shafts 13, and 70 the motive fluid divides, being compelled to actuate the pistons and their respective shafts in order to reach the exhaust ports 15. These two ports are preferably connected by an equalizing port or passage 16.

75 One of the shafts 13 carries a toothed pinion 17, the teeth of which mesh with the teeth of a gear wheel 18, which is attached to or carries a tool spindle 19, having a chuck 20, in which any suitable form of 80 tool such as a drill or anger, may be secured. The pinion 17 and gear wheel 18 are enclosed by a detachable cap 21, secured to the forward portion 22 of the frame, said cap 21 being provided with suitable bearings 85 for the extended ends of the shafts 13. This cap is also provided with a suitable bearing 23 for the tool spindle 19. The gear wheel 18 is preferably provided with the tail-bearing spindle 24, and with a combined thrust 90 and antifriction bearing 25, for taking the back thrust of the tool spindle.

95 My invention provides a simple and efficient form of pneumatic tool which can be readily grasped in the hand and held and manipulated at different angles, and which may be used for a variety of different purposes. While I prefer to use compressed air as a motive fluid, I do not necessarily limit myself thereto, as water or steam may 100 be employed as the motive fluid. It will also be understood that the particular type of motor employed may be varied, that shown being illustrative only.

105 If desired, the frame may be provided with perforated lugs or foot portions 26, by

means of which it can be fixed to a suitable base in case it should be desired to use the tool in this manner.

I claim:

- 5 1. A tool of the character described, comprising a frame, there being a motor chamber within said frame, a plurality of inter-geared pistons rotatably mounted in said chamber, there being an inlet conduit leading to said chamber, shafts to which the pistons are attached, a tool spindle out of alinement with the piston shafts, and gearing connecting one of said piston shafts with a tool shaft; substantially as described.
- 10 2. A tool of the character described, comprising a handle portion having an inlet conduit, a motor chamber carried by the handle portion, a casing connected to the front end of said handle portion, a plurality of shafts rotatably mounted in the handle portion and the gear casing, there being a piston chamber within the handle portion through which said shafts extend, a plurality of inter-geared rotary pistons in the 15 piston chamber connected to said shafts, a tool spindle out of alinement with the piston shafts and mounted in the handle portion and the gear casing, and gearing within the gear casing connecting one of the piston shafts with the tool spindle; substantially as described.
- 20 3. A portable tool of the character described, comprising a frame portion having a longitudinally extending piston chamber therein, there being a conduit leading to the piston chamber and a plurality of exhaust ports leading from the piston chamber;
- 25
- 30
- 35

ber, a gear casing connected to the front end of said frame portion, a plurality of shafts rotatably mounted in the frame portion and 40 the gear casing and extending through the piston chamber, a plurality of inter-geared pistons in the piston chamber connected to said shafts, a tool spindle out of alinement with the piston shafts and mounted in the 45 handle portion of the gear casing, and gears within the gear casing connected to one of the piston shafts and the tool spindle for drying the tool spindle; substantially as described.

4. A tool of the character described, comprising a handle portion connected to a frame portion, said handle portion being in the form of a hand grip, a motor chamber carried by the frame portion, there being an inlet conduit leading through the handle portion and the frame portion to the piston chamber, a plurality of exhaust ports leading from the cylinder chamber to the atmosphere, a valve for controlling the admission of fluid to the piston chamber, a tool spindle bearing seat in said frame portion, a gear frame connected to the front end of the handle frame having bearings for the motor and the tool spindle, and 60 gearing within said casing connecting the motor and the spindle; substantially as described.

In testimony whereof, I have hereunto set my hand.

ETHAN I. DODDS.
